UNITED STATES PATENT OFFICE.

SISSAG K. OUZOUN-BOGHOSSIAN, OF WASHINGTON, DISTRICT OF COLUMBIA.

DESIGN FOR A PHONOGRAPH-CABINET.

58,499.

Specification for Design.

Patented July 26, 1921.

Application filed March 28, 1921. Serial No. 456,500. Term of patent 3½ years.

To all whom it may concern:

Be it known that I, SISSAG K. OUZOUN-BOGHOSSIAN, a subject of the Sultan of Turkey, having declared my intention of becoming a citizen of the United States, residing at the city of Washington, District of Columbia, have invented a new, original, and ornamental Design for a Phonograph-Cabinet, of which the following is a specification, reference being had to the accompanying drawings, forming part hereof.

The Figure 1 is a front view and Fig. 2 is a side view of a phonograph-cabinet, showing my new design.

I claim:

The ornamental design for a phonograph-cabinet as shown.

In testimony whereof I affix my signature.

SISSAG K. OUZOUN-BOGHOSSIAN.
